(57) **CLAIM**

The ornamental design for an integrated audio system with a detachable base for use with a multi-user audio system, as shown.

DESCRIPTION

FIG. 1 is a front perspective view of an integrated audio system with a detachable base of the present invention for use with a multi-user audio system;

FIG. 2 is a front view of an integrated audio system with a detachable base of the present invention for use with a multi-user audio system;

FIG. 3 is a side view of an integrated audio system with a detachable base of the present invention for use with a multi-user audio system;

FIG. 4 is a back view of an integrated audio system with a detachable base of the present invention for use with a multi-user audio system;

FIG. 5 is a side view of an integrated audio system with a detachable base of the present invention for use with a multi-user audio system;

FIG. 6 is a bottom view of an integrated audio system with a detachable base of the present invention for use with a multi-user audio system; and,

FIG. 7 is a top view of an integrated audio system with a detachable base of the present invention for use with a multi-user audio system.

The broken lines shown in FIGS. 1, 3, 4, 5 and 6 of the drawings represent unclaimed portions of the integrated audio system with a detachable base and form no part of the claimed design.
